VICTOR R. DESPARD, OF HINSDALE, ILLINOIS, ASSIGNOR, BY MESNE ASSIGNMENTS, TO MCGILL MANUFACTURING COMPANY, OF VALPARAISO, INDIANA, A CORPORATION OF INDIANA.

LOCKING MEANS FOR SHELLS.

1,369,167.

Specification of Letters Patent. Patented Feb. 22, 1921.

Application filed April 6, 1918. Serial No. 227,111.

To all whom it may concern:

Be it known that I, VICTOR R. DESPARD, a citizen of the United States, residing at Hinsdale, in the county of DuPage and 5 State of Illinois, have invented a certain new and useful Improvement in Locking Means for Shells, of which the following is a full, clear, concise, and exact description, reference being had to the accompanying 10 drawings, forming a part of this specification.

My invention relates to locking means for shells, that is for locking shells and caps together so as to hold the incandescent socket 15 in position, an object being to provide an improved and simplified device of this character in which the cap and shell are securely held together under normal conditions but may be readily separated by manipulation 20 when desired. One of the features of my invention is an improved form of skirt on the cap and a coöperating collapsible end on the shell whereby all the parts are securely held together. In this connection I have 25 provided a conical circularly recessed skirt on the cap and a correspondingly formed shouldered portion at the end of the shell so that the shell may be inserted telescopically into the recess of the skirt where it is acted 30 upon by a lug on the interior of the skirt so as to lock the parts together.

Referring now more particularly to several preferred embodiments of my invention as illustrated in the accompanying drawing 35 in which like reference characters indicate like parts:

Figure 1 is a side elevation of one form of my invention showing the multiple position cap and shell assembled;

Fig. 2 shows the collapsible end of the shell;

Fig. 3 is a section along the line 3—3 of Fig. 2;

Fig. 4 is a section along the line 4—4 of Fig. 1;

Fig. 5 is a transverse section along the line 5—5 of Fig. 4;

Fig. 6 is a view looking upwardly into the interior of the cap removed from the shell;

Fig. 7 is a detail view of the adjustable lug carrying arm which is fitted inside the cap;

Fig. 8 is a detail view of the nipple which is staked in the cap;

Fig. 9 is a flanged collar which passes 55 through the lug arm and is secured to the interior of the cap by the nipple;

Fig. 10 is a side elevation of another form of my invention in which the shell and cap have but a single adjustment;

Fig. 11 is a section along the line 11—11 of Fig. 10;

Fig. 12 is a section along the line 12—12 of Fig. 11;

Fig. 13 is an interior view of the single 65 position cap;

Fig. 14 is a perspective view of the single position cap; and

Fig. 15 is a locking washer for the single 70 position cap.

Referring now to the first form of my invention as shown in Figs. 1 to 9, it comprises a shell 15 having the usual key slot 16 which is preferably enlarged at 17 so that the side edges thereof may engage the 75 outer edges of the locking lug hereinafter more fully referred to. The corners 18 of the slot are pressed inwardly slightly so as to properly pass the socket key. The lower end of the shell 15 is provided with a roll 80 thread adapted to receive a shade holder or similar device. The upper end of the shell is provided with a conical shouldered flange 19 adapted to be telescopically inserted into a correspondingly formed skirt 20 of the 85 cap 21, this skirt having its edge 22 drawn inwardly so as to form a shoulder and provide a circular recess in the skirt. Thus when the shell is inserted in the cap, it first collapses and as the shoulder on the flange 90 19 of the shell passes the edge 22 on the skirt, the shell again expands and snaps into holding position in the cap. When thus assembled the shoulder 23 on the flange 19 abuts inside the inturned edge 22 of the 95 skirt while the edge 24 of the flange 19 abuts the shoulder 25 of the skirt 20, the shell thus being firmly held against any rocking motion. The construction as thus far described would permit of a ready separation of the cap and shell by a longitudinal pull on the parts. That is, unless something is provided to prevent a normal collapse of the shell it may be readily withdrawn from the cap. But, in order to prevent such a 105 separation of the parts I provide a locking lug 26 which is carried within the cap and acts upon the edges 17 of the key slot,

this lug in the form of my invention shown in Figs. 1 to 9 being an adjustable lug 26 carried by a lug carrying arm or yoke 27, rotatably mounted within the cap and securely fastened thereto. For this purpose the nipple 28 carries a shank 29 adapted to be inserted through the central opening of the cap and extending through the central opening of a flanged hub 30 which hub 10 passes through the central opening of the bearing 31 in the lug carrying arm. The central opening of the cap 21 has a notched edge 32 as is also shown in Fig. 14, these notches and the notches 33 in the hub 30 15 corresponding so that the shank 29 on the nipple may be staked and pressed into the serrations as shown in Fig. 6. Thus the nipple and hub 30 are locked in the cap against rotation but the lug carrying arm 27 is free to be rotated within the cap, the lug 26 being preferably a pair of projecting elements adapted to snap into the perforation 34 in the skirt 20 so that the locking lug may be circumferentially adjusted into 20 any one of a plurality of positions. By means of this adjustment the shell and cap may be positioned in any one of many relative adjustments. In order to rotate the lug carrying arm into the desired position 25 a screw driver or similar tool is inserted at the point 35 (Fig. 6) between the lug and cap and the lug pushed away from the cap so as to be clear of the perforations 34 at which time the lug may be rotated into the 30 desired position and permitted to snap back into the proper perforations. An insulated lining 36 is provided in the cap being preferably the usual fiber lining which in the present case is snapped into the position 35 back of the lugs 37, 38 which are pressed out by the wall of the lug carrying arm. Thus the fiber lining is maintained in position and rotates with the lug carrying arm but maintains the cap suitably insulated 40 from the socket.

In assembling the cap and shell of the form shown in Figs. 1 to 9 the edge 24 of the collapsible end of the shell is simply placed inside the open end of the cap skirt 50 20, the slot 16 being first placed opposite the locking lug 26. The cap and shell are now telescopically pressed together, the shell collapsing, and as the shoulder 23 on the conical band of the shell passes the edge 22 55 of the cap skirt, the shell again expands and the band 19 snaps into the recess of the skirt. It is not necessary that the locking lug and shell slot line up when the parts are placed together because they snap together 60 whether they are lined up or not and if not lined up the shell is simply rotated in the cap until the edges 17 of the slot register with the lug 26, at which time the shell fully expands into locking position. It is 65 thus held against rotary adjustment and be-

cause of the coöperation between the locking lug 26 and the edges 17 of the slot the shell and cap cannot be separated by a direct longitudinal pull on account of the lug preventing a collapse of the shell. In order to 70 separate the parts the shell is first collapsed by pressing at either of the sides 39 until the corresponding edge 17 is clear of the lug 26, after which a slight rotary adjustment is given to the shell so that the inwardly 75 pressed side of the slot rests against the inner face of the lug 26. The shell is thus partly collapsed and may be separated from the cap by a direct longitudinal pull.

Figs. 10 to 15. 80

Referring now to the form of my invention as shown in Figs. 10 to 15 it differs from the form already described in that the cap and shell have but one position of assembly. That is, in the present form I do not provide an adjustable locking lug but simply depress portions of the metal at 40 and 41 of the cap 44 (Fig. 14), these depressions 85 acting the same as the lug 26 in that they coöperate with the edges of the slot in the shell to prevent its collapse. In this form of my invention the hub 29 on the nipple 28 is inserted through the central opening in the cap and through a washer 42 (Fig. 95 15), being then staked so that the nipple is locked against rotation in the cap. In order to hold the insulating lining 36 in the single position cap 44, a pair of ears 45, 46 (Fig. 11) are pressed inwardly from the cap so as 100 to hold the lining in place.

In this form of my invention, that is as shown in (Figs. 10 to 15) the same shell 15 may be used as in the first form described, the conical band on this shell and the recessed skirt 20 on the cap 44 being the same 105 shape in both forms. In assembling and separating the parts the operation is the same as described in connection with the first form of my invention. 110

For the purpose of illustrating my invention I have shown several preferred forms but I understand that changes and modifications will readily occur to those skilled in the art and therefore I do not desire to be 115 limited to the exact forms of my invention as shown and described but aim to cover all that which comes within the spirit and scope of the appended claims.

What I claim as new and desire to secure 120 by Letters Patent is:

1. A device of the character described comprising a cap having a conically recessed skirt, and a shell having a collapsible shouldered inturned end adapted to be telescopically inserted into the recess of the skirt. 125

2. A device of the character described comprising a cap having a recessed skirt, and a shell having a collapsible conical shouldered inturned end adapted to be tele- 130

scopically inserted into the recess of the skirt.

3. A device of the character described comprising a cap having a conical circularly recessed skirt, and a shell having a telescopic shouldered inturned end provided with means to engage within the recess of the cap.

4. A device of the character described comprising a cap having a conical circularly recessed skirt, and a collapsible shell having a telescopic shouldered inturned end conforming to the recess of the skirt and adapted to lock therein.

15 5. A device of the character described comprising a cap having a conical circularly recessed skirt, and a collapsible shell having a telescopic end conforming to the recess of

the skirt and adapted to lock therein and means to prevent relative longitudinal and 20 rotary movement of the cap and shell.

6. A device of the character described comprising a cap having a conical skirt with turned-in edge, and a telescopic shell having a shouldered conical band conforming to 25 the conical skirt and adapted to lock therein.

7. A device of the character described comprising a cap having a conically recessed skirt, and a shell having an inwardly movable shouldered inturned end for telescopic 30 insertion into the recess of the skirt, and means to prevent relative rotary movement of the cap and shell.

In witness whereof, I hereunto subscribe my name this 3rd day of April, A. D. 1918.

VICTOR R. DESPARD.
